UNITED STATES PATENT OFFICE.

GEORGE B. MAEGLY, OF KANSAS CITY, MISSOURI.

AIR-CUSHION.

1,255,327.

Specification of Letters Patent.

Patented Feb. 5, 1918.

Application filed January 23, 1914. Serial No. 314,928.

To all whom it may concern:

Be it known that I, GEORGE B. MAEGLY, a citizen of the United States, residing at Kansas City, in the county of Jackson and 5 State of Missouri, have invented certain new and useful Improvements in Air-Cushions; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to an air cushion for automobiles, or the like, and more particularly to a device for yieldingly supporting the body of a vehicle from its axles, and which is adapted for automatic adjustment 20 under varying or uneven loads to maintain the body at the proper elevation and level.

It is also an object of the invention to provide a device of this character which will not only directly cushion the body but which 25 will also absorb or cushion the rebound.

In accomplishing these and other objects of the invention, I have provided improved details of structure, the preferred forms of which are illustrated in the accompanying 30 drawings, wherein:—

Figure I is a sectional elevation of the chassis of an automobile equipped with air cushions constructed in accordance with my invention, taken on the line I—I, Fig. II.

35 Fig. II is a plan view of the same.

Fig. III is a vertical sectional view of one of the front cushions.

Fig. IV is a similar view of one of the rear cushions.

40 Fig. V is a transverse sectional view, taken on the line V—V, Fig. III.

Fig. VI is a detail perspective view of a valve trip mechanism.

Fig. VII is a transverse sectional view on 45 the line VII—VII, Fig. IV.

Referring more in detail to the parts:—

1 designates the frame, 2 the axles, 3 the wheels and 4 springs for pulling the axles and controlling lateral motion of the super- 50 structure.

Fixed on the frame 1, at each of the front corners of the vehicle, is a collar 5, and fixed in said collar, preferably by threading the

same thereinto, is a cylinder 6, having its lower end open and its upper end closed by 55 a head 7.

Slidably mounted in the cylinder and projecting through the open lower end thereof is a cylinder-piston 8 having a head 9 threaded in and closing its lower end, and provided with a socket bearing 10, within which the ball 11 is mounted for universal movement; the said ball being formed on the end of a connecting rod 12, having a like ball 13 on its lower end, seated in a socket 14 on 60 the front axle, whereby the cylinder piston is supported from the axle and adapted for universal movement relative thereto.

The upper end of the cylinder-piston, which is disposed within the cylinder 6, has 70 an inwardly extending flange 15 provided with a central opening of substantially the full diameter of the cylinder-piston, and threaded into said opening is a valve head 16 having an outwardly directed flange 17 overlying the inner end of the cylinder-piston, and clamping a packing leather, or the like, 75 18 thereto.

The valve head 16 comprises a downwardly directed portion 20; the head 16 having a large central aperture 21 and a plurality of small apertures 22 adjacent to and concentrically arranged around the large aperture, which serve as conduits for the passage of air from the intake chamber of 85 the cylinder to a rebound check chamber within the cylinder-piston, which will hereinafter be more fully described.

The head 7 of cylinder 6 is provided with a central aperture 24, and threaded into said 90 aperture and projecting into the cylinder is a tubular shaft 25, having an open inner end and a port 19 opening into the chamber A of the cylinder 6, above the head of the cylinder-piston.

95 Threaded into the upper end of the shaft 25 is a packing gland 26, that presses packing 33 against the top of bearing 30 (presently described), the upper end of which contains a check valve 27, through which air 100 under pressure may be delivered to the tubular shaft and into the cylinder. The bottom of the packing gland 26 is provided with a central aperture 28, and extending through said aperture is the seat 29 of a valve bearing 30, having a flange 31 seated on a shoulder 105

32 on the inner surface of the hollow shaft 25 and held in place by suitable packing and gland 26.

Extended centrally through the bearing member 30 is a channel 34, and slidably mounted in said channel is a valve stem 35, having a longitudinal groove 36 through which air may pass. 39 designates a suitable packing for valve 37, which seals the groove 36 when the valve is on its seat.

The lower end of the valve stem 35 is adapted for engagement by a valve lifter 40 having a head 41 which is slidably mounted within the shaft 25; a spring 42 being interposed between bearing 30 and valve lifter 40 to hold a cam 55, hereinafter referred to, normally on its seat 43.

The hollow shaft 25 extends downwardly within the cylinder, and through the central aperture 21 of the head 16 of the cylinder-piston and into the latter, where it is provided with a piston 44; said piston being preferably unpacked in order that air within the rebound check chamber B may leak slowly past the piston and into the shaft chamber C of the cylinder piston.

In aperture 21 and slidably mounted on shaft 25 is a sleeve valve 45, and threaded on said sleeve is a flange nut 46 for retaining a leather valve, or the like, 47, against a valve seat 48 in head 16.

49 designates a flange on one end of sleeve valve 45, and around the latter, and interposed between said flange and head 16, is a yieldingly tensioned spring 50 holding the packing leather 47 normally on its seat 48 and closing apertures 22.

The hollow shaft 25 is provided with an aperture 52, through which air may pass from chamber A, through the shaft, and into chamber C and thus maintain an equalized pressure in the cushion chambers A and C.

53 designates an exhaust port normally closed by piston 8, through which any surplus pressure of air is exhausted when the packing leather uncovers said port.

54 designates a pin pivotally holding a cam 55 in a slotted opening 56 in shaft 25. The cam 55 has a shouldered portion 57 for engagement with the sleeve valve 45.

With this construction applied to a vehicle, and the chambers containing the required pressure of air, any inequality of the road will cause the cylinder and the cylinder piston to telescope and flexibly absorb the shock.

It is well known, however, that after cushioning a sudden shock, the vehicle rebounds under the action of the springs, and to control this rebound I provide what I have termed a rebound control chamber, which operates automatically following the action of the cylinder in cushioning a shock. This rebound control chamber B is located between the head of the cylinder-piston and

the piston 44; it being apparent that when the cylinder and cylinder-piston telescope, the rebound volume of the chamber is enlarged and the capacity of chambers A and C is decreased, and that air contained in chambers A and C is compressed; the additional pressure in said chambers acting on the valve ring 47 to force said ring downwardly against the tension of the spring 50 and thereby uncover the conduits 22 in the ring body in the head of the cylinder-piston, admitting air to the rebound check chamber and again equalizing the pressure in the chambers, so that when the rebound occurs, the piston 44 will be returned to its normal position by the compressed air in the chambers A and C, and rebound of the vehicle retarded while surplus of air in chamber B leaks past the piston 44, and the pressure in the three chambers is again equalized.

In order to insure the desired flexibility and resiliency and also to carry the vehicle at a predetermined height, and the four corners at the same level under different loads, I have provided for automatically increasing or decreasing the pressure to regulate the volume of air within any of the individual cushions.

This mechanism comprises, in combination with the valve stem 42 and its head 41, a cam 55 which is pivotally mounted in a slot 56 in the sleeve 25 and provided with a shoulder 57 that projects beyond the plane of the shaft, so that it will engage the upper edge of the valve body 45 when the cylinder and cylinder-piston telescope sufficiently to bring the parts together.

The cam 55 is adapted when rocked on its pivot, to engage the head of the valve lifter 40, raise the valve from its seat, so that air may be automatically admitted through the check plug 27 into the intake chamber and fill chambers A and C until the parts are expanded sufficiently to lift the vehicle to a normal riding height, when the sleeve valve 45 passes out of engagement with cam 55 and valve 37 and is permitted to regain its seat.

The valve in plug 27 is provided with a conduit 59 which leads to a supply tank 60, that may be carried on any portion of the vehicle, so as to be in condition to supply the cushions at all times. The cushions on the rear portion of the frame are substantially identical in construction with those on the front, except that they are preferably inverted and provided with ball and socket connection with both the body and axles.

In using the device, presuming the parts to be constructed and assembled as described, and connected with a supply tank, the load on the cushions will collapse the latter, so that the cams 55 are engaged by the sleeves 45 and rocked on their pivots until they engage lifter 40 for valve stem 130

35 and lift valve 37 off its seat to admit air to the intake chamber, from which it flows through the hollow shaft 25 to the chamber C and forces the cylinder-piston 5 outwardly until the parts are spread sufficiently to separate the cam from its engagement with the collar and allow the valve to close automatically.

With the parts in this condition, compressed air within the cylinder and cylinder-piston forms a cushion that absorbs shocks encountered by the vehicle; the admission of air being sufficient to operate the piston under ordinary conditions.

15 In practice, with any telescopic action of the cushion, the chambers A and C are contracted, and the pressure increased; while chamber B is expanded, and the pressure reduced. When this action occurs, the pressure 20 sure in chamber C equalizes with that in chamber A through the hollow piston rod, and this in turn equalizing with pressure in chamber B through apertures 22, upon the unseating of valve 47.

25 Having thus described my invention, what I claim as new therein, and desire to secure by Letters-Patent, is:

1. The combination with a source of supply for compressed fluid, of a telescopic air spring comprising two pistons adapted for inverse variation, and forming a pneumatic rebound cushion intermediate the two pistons.

2. The combination with a supply of compressed fluid, of a telescopic air spring comprising two pistons adapted for inverse variation, and forming a pneumatic rebound cushion intermediate the two pistons, and automatic means for establishing and closing communication between the said fluid supply and air spring.

3. The combination with a supply of compressed fluid, of a telescopic air spring having two pistons adapted for inverse variations, a pneumatic rebound cushion formed by, and intermediate, the two pistons, and means operable upon variation of the pistons for supplying and reducing fluid pressure within the spring.

50 4. The combination with a supply of compressed fluid, of a telescopic air spring having two pistons adapted for inverse variations, a pneumatic rebound cushion formed by, and intermediate, the two pistons, and means operable upon variation of the pistons for supplying and reducing fluid pressure within the spring, the said means being adapted for automatically varying the pressure in order to maintain a predetermined 55 volume of fluid within the said spring.

5. In a device of the character described an air spring adapted for sustaining a load and comprising a rebound chamber interposed between two load carrying chambers, 60 means for supplying fluid under pressure to

a load carrying chamber, means for equalizing the pressure between the chambers, and means adapted for actuation by variations in the load for automatically varying the pressure to normally maintain a predetermined volume in the three chambers. 70

6. The combination with a source of fluid supply, of an air cushion adapted for telescopic movement, having a secondary chamber interposing two primary chambers, a 75 tubular piston rod for establishing communication between the chambers, a cam pivotally mounted within the rod, a normally seated valve, and means adapted for actuating the cam to unseat the valve upon 80 telescopic movement of the cushion.

7. The combination with a load-carrying body frame and running gear, of a telescopic air spring comprising a rebound chamber interposing two load carrying 85 chambers, a source of supply for compressed fluid, a conduit connecting the source of supply with one of said chambers, and a valve in said conduit adapted for actuation by variations in the load, for automatically 90 varying the pressure to maintain a predetermined volume in the three chambers.

8. A device of the character described, comprising initial cushions, and a rebound cushion interposed between the initial cushions, all of said cushions being adapted for variation under varying loads, means for supplying a pressure medium to the cushions, and means automatically operable upon variation of position of the cushions for controlling said supply means. 95

9. A device of the character described, comprising spaced initial cushions, and a rebound cushion interposed between the initial cushions and adapted for inverse variation 105 relative thereto, and an automatically operable valve for equalizing the pressure of the medium within the cushions irrespective of the magnitude of variation of volume in said cushions.

10. A device of the character described, comprising spaced initial cushions, and a rebound cushion interposed between the initial cushions and adapted for inverse variation relative thereto, and an automatic valve for 115 equalizing the pressure between said cushions. 110

11. A device of the character described, comprising two initial and an intermediate rebound cushion adapted for inverse variations, and a valve operable by increased pressure in one of the initial cushions, to establish communication between the cushions, for the purpose set forth. 120

12. A device of the character described comprising initial and rebound cushions, means for supplying air under pressure to said initial cushion, a valve for equalizing the pressure between said initial and rebound cushions, and a second valve adapted 125 130

for actuation upon actuation of said cushions for governing the flow of air through said air supply means.

13. The combination with a cylinder, of 5 a hollow piston slidably mounted within the cylinder, a tubular shaft fixed in the cylinder and slidable in the hollow piston and having laterally opening apertures above said piston to establish communication 10 between the cylinder and piston chambers, and a piston on said tubular shaft dividing the hollow piston into separate variable chambers, for the purpose set forth.

14. The combination with a cylinder, of 15 a hollow piston slidably mounted within the cylinder, a tubular shaft fixed in the cylinder and slidable in the piston to establish communication between the cylinder and hollow piston, a piston on said shaft dividing the piston chamber into separate variable chambers, and an automatic valve for establishing communication between a piston chamber and the cylinder chamber.

15. The combination with a cylinder, of 25 a hollow piston slidably mounted within the cylinder and having apertures for establishing communication between the cylinder and piston chambers, a hollow shaft fixed in the head of the cylinder and slidably projected through the piston head, a piston on said shaft dividing the interior of the hollow piston into separate variable chambers, and an automatic valve controlling flow of air through the apertures in the piston head.

16. The combination with a cylinder having an air supply pipe concentric with and extending into said cylinder, of means for supplying air to the interior of said cylinder through said pipe, a valve in said pipe for 40 controlling the flow of air from said supply means, a hollow piston slidably mounted within said cylinder, and having communication with said cylinder through said pipe, a piston on said pipe, slidably mounted in said hollow piston and adapted to inclose 45 a rebound chamber, and an automatic valve in said hollow piston for simultaneously actuating said air supply valve and equalizing the pressure between said cylinder, hollow piston and rebound chamber, for the 50 purpose set forth.

17. The combination with a cylinder and a hollow piston having a head, of a hollow shaft contained within the cylinder, means 55 for supplying air through said shaft to the cylinder, a normally seated valve for controlling said supply, a cam pivotally mounted within said shaft, and a valve body slidably mounted on said shaft and movable 60 with said piston head and adapted for actuating said cam to unseat the valve, for the purpose set forth.

18. The combination with a cylinder, of a tubular shaft mounted within the cylinder 65 and provided with slots, means for supply-

ing air to said cylinder through the shaft, a cam pivotally mounted in the slots, a sleeve valve slidably mounted on the shaft and adapted for engagement with the cam, and a valve lifter slidably mounted in the shaft 70 and adapted for engagement with the air supplying means.

19. An air cushion comprising a cylinder, a hollow piston for said cylinder, a tubular shaft concentrically mounted in said cylinder, and extending into said hollow piston for equalizing the pressure in the cylinder and piston, a piston on said shaft adapted for reciprocatory movement in said hollow piston, and means for conducting air to said 80 cylinder.

20. An air cushion comprising a cylinder, a hollow piston for said cylinder, a tubular shaft rigidly mounted in and concentric with said cylinder, a solid piston on said shaft 85 adapted for reciprocatory movement in said hollow piston, a valve in said hollow piston between said solid piston and said cylinder, and means for conducting air to said cylinder and hollow piston.

21. An air cushion comprising a cylinder, a hollow piston for said cylinder, a tubular shaft rigidly mounted in said cylinder and extending into said hollow piston, a valve in said tubular shaft, and a cam operable by 95 said hollow piston for opening said valve.

22. An air cushion comprising a cylinder, a hollow piston with a removable head for said cylinder, a tubular shaft rigidly mounted in said cylinder and extending through its head and into said hollow piston, a solid piston on said shaft adapted for reciprocatory movement in said hollow piston, an air inlet valve in said tubular shaft, and a cam in said tubular shaft operable by said hollow 100 piston for opening said valve to admit air under pressure in sufficient quantity to expand the parts and allow said valve to close automatically.

23. An air cushion comprising a cylinder, 110 a hollow piston slidably mounted in and forming a chamber in said cylinder, a tubular shaft rigidly mounted in said cylinder and extending into said hollow piston, and having apertures above said piston for establishing communication between said cylinder and hollow piston, a solid piston on said tubular shaft slidably mounted in and dividing said hollow piston into two chambers, means for conducting air to said cylinder 120 chamber and to one of the two chambers, and means for conducting air to and temporarily confining the same in the other of said chambers.

24. An air cushion comprising a cylinder, 125 a hollow piston slidably mounted in and forming a chamber in said cylinder, a tubular shaft rigidly mounted in said cylinder and extending into said hollow piston, a solid piston on said shaft for dividing said 130

hollow piston into two chambers, a valve in one end of said hollow piston communicating with said cylinder chamber and one of said piston chambers, for temporarily confining air in said piston chamber, and means for initially equalizing pressure in all of said chambers.

25. In an air cushion, the combination with a hollow piston having closed and 10 apertured ends, of a cylinder slidably mounted on said piston, a tubular shaft rigidly mounted in said cylinder and slidably mounted in the apertured end of said piston and having a laterally opening aperture located outside of said hollow piston, a solid 15 piston on said shaft slidably mounted within said hollow piston and adapted for coöperation with the apertured end of said hollow piston to form a rebound chamber, and 20 means for supplying air under pressure to said cylinder, hollow piston and rebound chamber.

26. An air cushion comprising a cylinder, a hollow piston slidably mounted in and 25 forming a chamber in said cylinder, a solid piston slidably mounted in and dividing said hollow piston into two chambers, a tubular shaft rigidly connected with said cylinder and with said solid piston for establishing free pneumatic communication between said cylinder chamber and one of said 30 piston chambers, and a spring-pressed valve in said hollow piston for establishing pneumatic communication in one direction between said cylinder chamber and one of said 35 piston chambers.

27. An air cushion comprising a cylinder, a hollow piston slidably mounted in said cylinder and inclosing a chamber therein, a 40 solid piston slidably mounted in and divid-

ing the interior of said hollow piston into piston and rebound chambers, a tubular shaft rigidly mounted in said cylinder, slidably mounted in said hollow piston and rigidly connected with said solid piston, and having an aperture located outside of said hollow piston and adapted to establish communication between said cylinder chamber and piston chamber, and an automatic valve between said cylinder and rebound chambers, 45 said hollow piston being slidable in said cylinder in such manner that the volume of the rebound chamber increases or decreases in proportion to the decrease or increase in volume of the cylinder and piston chambers. 50

28. An air cushion comprising a cylinder, a hollow piston slidably mounted in said cylinder and having a closed end, a cup washer on the other end of said piston, a plug having a plurality of apertures threaded into said piston and adapted to hold said washer in functional position, an apertured valve slidably mounted in one of the apertures in said plug, and having a flange adapted to close the other apertures in said 60 plug, a spring for yieldingly holding said valve in closed position, a tubular shaft rigidly mounted in said cylinder and slidably mounted in said apertured valve, a solid piston on said tubular shaft and slidably mounted in said hollow piston, and means for introducing air under pressure to said cylinder and hollow piston. 65

In testimony whereof I affix my signature in presence of two witnesses.
